UNITED STATES PATENT OFFICE

HERMAN G. BLOSSER, OF PITTSBURGH, PENNSYLVANIA

DESIGN FOR A COMBINED REACTANCE COIL AND SUPPORT THEREFOR

Application filed June 18, 1930. Serial No. 36,092. Term of patent 14 years.

To all whom it may concern:

Be it known that I, HERMAN G. BLOSSER, a citizen of the United States, residing at Pittsburgh, in the county of Allegheny and State of Pennsylvania, have invented a new original, and ornamental Design for Combined Reactance Coils and Supports Therefor, of which the following is a specification, reference being had to the accompanying drawing, forming part thereof.

In the drawing:

Fig. 1 is a front view of the combined reactance coil and support therefor, and
Fig. 2 is a side view thereof.

I claim:

The ornamental design for a combined reactance coil and support therefor, as shown.

HERMAN G. BLOSSER.
